UNITED STATES PATENT OFFICE.

CHARLES W. COX, OF WINCHESTER, INDIANA.

GATE.

1,156,275.

Specification of Letters Patent.

Patented Oct. 12, 1915.

Application filed December 15, 1914. Serial No. 877,362.

To all whom it may concern:

Be it known that I, CHARLES W. Cox, a citizen of the United States, residing at Winchester, in the county of Randolph and State of Indiana, have invented a new and useful Gate, of which the following is a specification.

The present invention appertains to gates, and aims to provide a novel and improved farm gate.

A specific object of the invention, is to provide a gate of such novel construction, that the free end thereof may be swung upwardly and downwardly and held at various positions, in order that the gate may be held at various inclined positions if desirable or necessary. It is also within the scope of the invention, to provide a gate of the nature indicated, which will be comparatively simple, substantial, non-encumbering and inexpensive in construction, as well as being convenient, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in its preferred embodiment in the accompanying drawing, wherein—

Figure 1 is a side elevation of the improved gate. Fig. 2 is a sectional view of the gate, taken on the line 2—2 of Fig. 1. Fig. 3 is a fragmental view of the gate in raised position, parts being shown in section. Fig. 4 is a cross section of the gate, taken on the line 4—4 of Fig. 1. Fig. 5 is an enlarged cross sectional detail taken on the line 5—5 of Fig. 1.

The gate proper comprises a vertical series of suitably spaced or arranged rails or bars 1, and a longitudinal series of suitably spaced or arranged parallel stiles 2, pivoted to the rails 1, by means of rivets or other pivot elements 3. The stiles 2 are preferably formed from straps or strips of metal doubled, with their bends disposed uppermost, and having their limbs or sections projecting over the opposite sides of the rails 1 and bearing thereagainst. Thus,

the rails 1 are pivoted between the limbs or sections of the stiles or doubled straps or strips 2.

The device for hanging or mounting the gate in order to hinge the same to the gate post P, and in order to enable the gate to be adjusted vertically, embodies upper and lower hangers or bearings 4 and 5 in the form of eye bolts having their shanks engaged into or through the post P and having their eyes or bearing portions coaxial or in alinement. Telescoping tubes 6 and 7 are journaled through the bearings or hangers 4 and 5, the upper and outer tube 6 being journaled through the bearing 4, and the inner and lower tube 7 being engaged through the bearing 5. The lower tube 7 is held against vertical movement by means of a suitable pin or retaining element 8 engaged through the tube 7 and engaging over and under the bearing 5. The lower end of the upper tube 6 terminates short of the lower bearing 5, while the upper end of the lower tube 7 terminates within the tube 6 in the vicinity of the upper bearing 4, so that the upper tube 6 in sliding through the bearing 4 and upon the lower tube 7, will be supported in a substantial and vertically adjustable manner, as well as being permitted to rotate.

The lower portion of the gate is provided with means embracing the tube 7 immediately below the tube 6, and to this end an eye bolt 9 has its eye 10 embracing the tube 7 at a point slightly below the lower end of the tube 6, and has its shank 11 projecting between the sections or portions of the stile 2 at that end of the gate adjacent the tubes 6 and 7.

Clamping plates 12 are slidably mounted upon the shank 11 of the eye bolt 9 and bear against the edges of the said stile 2, and have angular ends or flanges 13 overlapping the sides of the said stile, and clamping nuts 14 are threaded upon the shank 11 and seat against the plates 12 for clamping the parts together and holding the eye bolt 9 rigidly in place, so that the said eye bolt in being slidably and rotatably engaged to the tube 7, will assist in supporting and bracing the gate.

The upper portion of the gate is provided with means co-operating with the tubes 6 and 7 for supporting the gate, and to this end a doubled hanger bar 15 has its bend 110

or loop extending around the tube 6 above the bearing 4, and pivoted to the said tube, by means of a rivet or pivot pin 16 engaged through the sections or side portions of the bar 15 and the tube 6. The sections or side portions of the bar 15 are pivoted to the rivet or pivot member 3 at the adjacent upper corner of the gate, and are also secured together below the upper or adjacent rail 1, as at 17. One of the sections or side portions of the bar 15 is extended obliquely or diagonally downward toward the free end of the gate to the next lower rail 1, as at 18, and has its free end engaging and bearing 15 slidably upon the respective rail 1, as clearly apparent by reference to Fig. 1. The upper edge of the extension 18 is provided with notches 19, whereby the portion 18 forms an inclined rack, the free end of the extension 20 or rack 18 having a depending fork 20 straddling the respective rail 1 and guiding the extension or rack 18 for sliding movement upon the rail.

As a means for supporting the free end 25 of the gate at various vertical positions with the gate either horizontal or inclined, the doubled rod 21 has terminal eyes 22 pivoted to one of the lower rivets or pivot elements 3, of the gate remote from the hinged end 30 thereof, and having its sections or side portions disposed at the opposite sides of the gate, with the bend of the rod 21 arranged adjacent the notches or teeth 19 of the rack 18 to engage the same. The rack 18 and rod 21 are in alinement, they being disposed 35 obliquely or diagonally, so as to support the free end of the gate in an effective manner.

The free end of the gate may be provided 40 with any suitable latch 23 which is engageable with a keeper 24 carried by the post S.

The hanger bar 15 and eye bolt or hanger element 9 which are engaged to the respective end of the gate, and which are engaged to the telescoping tubes 6 and 7, will support the gate in a substantial manner, and 45 allow the same to swing toward one side or the other. It is to be noted that the eye bolt 9 being journaled upon and embracing the tube 7 may swing readily below the said 50 tube when the gate is swung, and the hanger bar 15 being pivoted or secured to the tube 6 by the rivet or pivot element 16, will cause the tube 6 to be swung with the gate within the bearing 4 and upon the lower tube 7.

55 The doubled supporting rod 21 having its bend or bight engaged to the rack 18 of the hanger bar 15, will support the gate at the horizontal or inclined position to which it has been adjusted, and by disengaging the 60 bend of the rod 21 from the rack 18, the free end of the gate may be either raised or lowered to adjust the position of the gate as desired, and when the rod 21 is again engaged to the rack 18, the gate will be held at 65 the newly adjusted position. It is thus pos-

sible to hold the gate either horizontal, or at an angle of inclination to suit hilly or un-level ground, or accommodate an inclined gate post. In this connection, it is to be observed, that when the free end of the gate is 70 swung upwardly and downwardly, the hanger bar 15 being pivoted to the gate and hinge tube 6, will cause the rack to swing and slide upon the respective rail 1 of the gate, during the vertical swinging movement of the gate, the rack being guided upon the respective rail by means of the fork 20.

To lift or elevate the gate bodily, the same is raised in any suitable manner so that the 80 tube 6 and eye bolt 9 carried by the gate will slide upwardly upon the tube 7, the tube 6 sliding within the upper bearing 4. The gate may then be held at the elevated position, by means of a pin 25 engaged through one of the series of apertures 26 provided in the tube 7, so that the pin 25 will be disposed between the lower end of the tube 6 and the eye bolt 9, for preventing the upward as well as the downward movement of 90 the gate, but to enable the gate to swing back and forth. Thus, when the gate is elevated, it will allow small animals or farm stock to pass thereunder, whereas the larger animals will be excluded from passage 95 through the gate way, and the gate cannot be forcibly raised by the animals getting under and forcing it upward, since the pin or holding element 25 will prevent this action. The pin 25 is also preferably engaged 100 through the respective aperture 26 when the gate is in its lowermost or normal position, as seen in Fig. 1.

The gate may also be swung toward either side, and to this end, the free end of the gate 105 may be moved past the striking post S, by swinging the gate vertically so that the free ends of the rails 1 are retracted sufficiently to swing past the post S, and in this event, the gate may be returned to normal position. 110

The construction of the gate and its mounting is such that the strains are taken up in a most desirable manner, to relieve the gate proper of injurious strains, and the construction and assemblage of the component parts of the device are such as to prevent the same from being readily injured. The parts of the mounting are also protected from being clogged or otherwise impaired, and the gate will be serviceable during the 115 winter season, as well as at other periods. The upper end of the tubular member 6 is preferably flattened and welded or otherwise secured, to close the same, and to provide an ornamental head therefor. 120

Having thus described the invention, what is claimed is:—

1. In a gate structure, a gate comprising rails and stiles pivoted together, a hanger bar pivoted to the gate and having an in- 130

clined rack slidably engaging one of the rails, and an inclined rod pivoted to the gate and engageable with the rack, the rod and rack being approximately in alinement.

5 2. In a gate structure, a gate comprising rails and stiles pivoted together, a hanger bar pivoted to the gate and having an inclined rack having a fork at its lower end straddling and slidably engaging one of the
10 rails, and an inclined rod pivoted to the gate

and engageable with the rack, the rod and rack being approximately in alinement.

In testimony that I claim the foregoing as my own, I have hereto affixed my signature in the presence of two witnesses.

CHARLES W. COX.
